(57) CLAIM

We claim the ornamental design for a shaving razor, substantially as shown and described.

DESCRIPTION

FIG. 1 is a perspective view of the shaving razor showing the new design;

FIG. 2 is a front view of the shaving razor;

FIG. 3 is a rear view of the shaving razor;

FIG. 4 is a side view of the shaving razor;

FIG. 5 is another side view of the shaving razor;

FIG. 6 is a top view of the shaving razor; and,

FIG. 7 is a bottom view of the shaving razor.

The broken lines are for illustrative purposes only and form no part of the claimed design.
